ADJUSTABLE STEP-DOWN TRANSFORMER FOR USE IN ELECTRICAL MEASURING

Raymond J. Feldman, Bronx, N.Y., assignor to
SOS Consolidated, Inc., Birmingham, Mich.

Filed Nov. 17, 1971, Ser. No. 199,830

Term of patent 14 years

Int. Cl. D10—05; D13—02

U.S. Cl. D26—1 Q

FIG. 1
FIG. 2

FIG. 4

FIG. 5

FIG. 8

FIG. 7

FIG. 6

FIG. 1 is a front view of an adjustable step-down transformer and positioning bracket for use in measuring high-amperage currents with clamp-around instrument showing my new design.

FIG. 2 is a side view thereof.

FIG. 3 is a bottom plan view thereof.

FIG. 4 is a rear view thereof.

FIG. 5 is a section of FIG. 1 taken along line 5—5 thereof.

FIG. 6 is a side elevation of the transformer illustrated in FIG. 7, with portions omitted for convenience of illustration.

FIG. 7 is a front view of the step-down transformer in an alternate position from that shown in FIG. 1.

FIG. 8 is a top plan view thereof.

I claim:

The ornamental design for an adjustable step-down transformer for use in electrical measuring, as shown.
